UNITED STATES PATENT OFFICE

REGINALD M. RAYNOLDS, OF NEW YORK, N. Y., ASSIGNOR TO MCMLIAN BOOK COMPANY, OF SYRACUSE, NEW YORK, A CORPORATION OF NEW YORK

LEAF FLIPPER

Application filed October 13, 1928. Serial No. 312,240.

This invention relates to a new and improved leaf flipper for use with loose leaf binders and is particularly well adapted to be used with loose leaf binders of the split 5 ring or arcuate prong type.

When binders of this type are open and it is desired to close them by moving the covers towards each other such movement of the covers will move the sheets in the binder 10 around the binder rings or prongs. The sheets of such binder are held in position by virtue of the fact that they are provided with apertures along a longitudinal edge in which the rings or prongs are positioned, such 15 apertures usually being circular in shape and of a diameter slightly larger than the ring or prong which extends through them.

In binders of this type the rings or prongs are usually positioned on a back member to 20 the outside edges of which are hinged the covers of the binder with the result that the portions of the sheets with which the rings or prongs are engaged are positioned between the hinges of the covers so that when the 25 covers are raised for the purpose of closing the binder the outer edges of the sheets will be raised above the inner edges of the sheets with the result that the rings or prongs will assume an oblique position with reference to 30 the apertures in the sheets which will cause the sheets to bind on the rings or prongs to a certain degree and resist movement around such rings or prongs. The sheets usually used with this type of binder being thin there is 35 considerable possibility of injury to the sheets when they are thus forced along the rings or prongs, which is particularly true of the sheets which are adjacent to the covers.

In order to permit the movement of the 40 sheets along the rings or prongs it is desirable to provide a means which will provide a support for the leaves during such movement and which will also hold the leaves in such a position with reference to the rings 45 or prongs that there will be no tendency of the leaves to bind on the prongs during their movement, and the main object of my invention is to provide a device which may be interposed between the leaves of a binder and 50 the covers of the binder to act as a support

and guiding means for the leaves while the binder is being closed.

Other objects and advantages relate to the size, shape and arrangement of parts all as will more fully appear from the following 55 description taken in connection with the accompanying drawings, in which:

Figure 1 is a perspective view of the preferred form of my device.

Figure 2 is a top plan view, partially broken 60 away and partially in section, showing two of my devices in position on a binder with a leaf in position on one of such devices.

Figure 3 is a section on line 3—3 of Figure 2. 65

Figures 4, 6 and 8 are perspective views of modified forms of my device.

Figure 5 is a section on line 5—5 of Figure 4.

Figure 7 is a section on line 7—7 of Figure 6. 70

Figure 9 is a section on line 9—9 of Figure 8.

Figure 10 is another modified form of my 75 device.

Figure 11 is a section on line 11—11 of Figure 10.

For the purpose of explaining the construction and operation of my device I have here shown one type of a split ring binder 1 comprising a back member 2 and covers 3 and 4 connected to back member 2 by flexible hinges 5 and 6 respectively. A curved spring plate 7 is affixed to the upper surface of back member 2 by rivets or other convenient means, not shown. Spring plate —7— has its opposite longitudinal edges return bent to form channels 8 and 9. A toggle plate 10 having affixed thereto a plurality, in this case shown as five, of half rings 11 is positioned on back member 2 with one longitudinal edge in channel 9 of spring plate 7. A second toggle plate 12 having affixed thereto a plurality, in this case shown as five, of half rings 13 is similarly positioned on back member 2 with its outer longitudinal edge in channel 8 of spring plate 7. A plurality of double headed buttons 14, one only being shown, are positioned between the inner longitudinal edges of toggle plates 10 and 12 with such edges be- 100

- tween the heads of the buttons 14. The combined width toggle plates 10 and 12 is slightly greater than the distance between channels 8 and 9 of spring plate 7 so that when the inner longitudinal edges of toggle plates 10 and 12 are below the outer longitudinal edges of such plates, in which position the upper end of half rings 11 and 13 are in contact, the parts will be held in this position by the pressure of spring plate 7. When it is desired to raise the inner longitudinal edges of toggle plates 10 and 12 above the outer longitudinal edges of such plates to separate half rings 11 and 13 such movement is permitted by the resiliency of spring plate 7, and when such movement has been completed the parts will be yieldingly held in that position by the pressure of spring plate 7. The movement downwardly of the inner longitudinal edges of toggle plates 10 and 12 and the corresponding upward movement is limited by the buttons 14 which permit only a limited movement of the edges of toggle plates 10 and 12 between the heads of buttons 14.
- 25 A curved cover plate 15 is positioned above toggle plates 10 and 12. Cover plate 15 has its longitudinal edges return bent so that it may be sprung over the longitudinal edges of spring plate 7 and be held securely in that position. Cover plate 15 is provided with slots 16 and 17 to permit the movement therethrough of half rings 11 and 13 as the same are closed and opened. The upper end of half ring 11 is V-shape in form so that it may enter a V-shaped slot in the upper end of half ring 13 when the two rings are brought together, half rings 11 and 13 being so positioned on toggle plates 10 and 12 respectively that half ring 11 will register with opposing half ring 13.
- The preferred form of my device, as perhaps may best be seen from Figure 1, consists of a substantially rectangular shaped body 18 made of metal or fibre or other sufficiently stiff material. Body 18 is provided with a plurality, in this case shown as five, of oval apertures 19 so positioned that they will register with either half rings 11 or half rings 13 when the body 18 is placed in position in the binder. Cover 18 is formed with an approximately V-shaped trough 20 positioned between apertures 19 and the edge of body 18. Trough 20 is so formed as to provide a vertical ledge or stop 21 adjacent apertures 19 and in spaced relation thereto. In use it is desirable to use two of my devices, one cooperating with each of the covers of the binder, and I have here shown in Figure 3 one of my devices in position on cover 3 with no leaves thereon and a second one of my devices in position on cover 4 with a plurality of leaves 23 in position on the device.

The leaves 23 are provided with apertures 24 so positioned as to register with half rings 11 or 13, and for a purpose hereinafter to be described it is desirable to have the distance between the centers of apertures 24 and the longitudinal edge of the sheet greater than the distance between ledge 21 and the center of oval apertures 19.

When the parts are in the position shown in Figure 3 and cover 3 is raised for the purpose of closing the binder it will raise with it the outer edge of body 18 which will cause the outer end of aperture 19 to contact with half ring 13 and ride upwardly thereon, the inner end of body 18 moving outwardly along the upper surface of cover plate 15 to guide body 18 in its upward movement. The notches 22 are provided so that when the lower edge of body 18 has moved outwardly to the inner side of half rings 13, half rings 13 will enter notches 22 to permit the lower end of body 15 to continue to move outwardly, which will permit body 18 to continue its upward movement on half rings 13 without any binding of apertures 19 on half ring 13.

When cover 4 is raised in a similar manner the body 18 will move upwardly in the same way as the body 18 moved upwardly on cover 3 as just described, and in doing so it will carry upward with it the sheets 23 which are positioned on its upper surface. The relation of parts is such that the inner longitudinal edges of sheets 23 will rest against the ledge 21 on body 18, and inasmuch as the distance, as just described, between the inner longitudinal edges of sheets 23 and the centers of apertures 24 is greater than the distance between ledge 21 and the centers of apertures 19 the apertures 24 in sheets 23 will be held in such a position that the outer edges of apertures 24 will be in spaced relation to the outer surfaces of half rings 11 and there will be no tendency for apertures 24 to bind on half rings 11.

In Figure 3 I have shown in heavy lines the binder in the open position and in dotted lines the binder in the partially closed position.

In Figures 4, 6 and 8 I have shown modified forms of my device which are designed to function in a similar manner as the manner in which the device shown in Figure 1 functions, the difference being that I form my ledge or stop in a different manner.

In Figure 4 I show a body 25 having oval apertures 26 similar to apertures 19 and having notches 27 similar to notches 22 but in this embodiment of my invention I form the ledge or stop 28 by bending a portion of the edge of body 25 at right angles to such body 25 and by then bending the outside edge of body 25 into a plane parallel with the plane in which the main portion of body 25 is disposed.

In Figure 6 I show a body 29 provided with oval apertures 30 similar to apertures 19

and with notches 31 similar to notches 22 but in this case I form my ledge or stop 32 from a separate V-shaped member 33 which is affixed to the upper surface of body 29 by rivets 34 or other convenient means.

5 In Figure 8 I show still another embodiment of my invention consisting of a body 35 with oval apertures 36 similar to apertures 19 and having notches 37 similar to notches 22. In this embodiment a series of stops 38 are formed by return bending onto the upper surface of body 35 the material which was struck therefrom to form slots 37.

10 In Figure 10 I show a device similar to the device shown in Figure 4 having a body 39, spaced apertures 40, slots 41 and a ledge or stop 42. In this embodiment, however, the edge of body 39 which carries slots 41 is curved downwardly towards the plane in 15 which the main body 39 is disposed so that the inner edge of my device will more quickly contact with cover plate 15 when the covers 3 and 4 of the book are raised.

15 It will be understood that the material from which my device is constructed may be varied as desired and it will also be understood that the size, number and relative position of the oval apertures 19 and the notches 22 and the similar apertures and notches shown in 20 Figures 4, 6, 8, and 10, and also the height and relative position of the ledge or stop 20 and the similar ledges or stops 28, 32, 38 and 42 may be varied as desired to adapt my device to be used with different types of binders, 25 for altho I have shown and described a specific structure and form of part as an exemplification of embodiments of my invention I do not desire to restrict myself to the exact size, shape or relation of parts as various changes may be made within the scope of 30 the appended claims.

35 What I claim is:

1. In a device of the class described, a substantially rectangular plate having a plurality of spaced oval apertures with their axes on a line parallel with one edge of the plate, such edge having a plurality of spaced notches in alinement with the oval apertures.

2. In a device of the class described, a substantially rectangular plate having a plurality of spaced oval apertures with their axes on a line parallel with one edge of the plate, and a vertical ledge positioned between the apertures and the edge of the plate and being substantially parallel with such edge, such edge having a plurality of spaced notches in alinement with the oval apertures.

3. In a device of the class described, a substantially rectangular plate having a plurality of spaced apertures with their axes on a line parallel with one edge of the plate, and a ledge positioned between the apertures and the edge of the plate and being substantially parallel with such edge, such edge having a

plurality of spaced notches in alinement with the spaced apertures.

In witness whereof I have hereunto set my hand this 26th day of September, 1928.

REGINALD M. RAYNOLDS.
